DESIGN FOR AN AUTOMOBILE

Douglas Frederick Harold Fitzmaurice,
London, England

Application February 14, 1936, Serial No. 61,177
In Great Britain May 29, 1935

Term of patent 14 years

To all whom it may concern:

Be it known that I, Douglas Frederick Harold Fitzmaurice, a subject of the King of Great Britain, residing at London, England, whose post-office address is 122 A High Street, St. Johns Wood N. W. 8, London, England, have invented a new, original, and ornamental Design for an Automobile, of which the following is a specification, reference being had to the accompanying drawing forming a part thereof.

In the drawing:

Fig. 1 is a perspective view taken from the front side of the right side of the automobile.

Fig. 2 is a perspective view taken from the left side of the rear of the automobile.

I claim:

The ornamental design for an automobile as shown.

DOUGLAS FREDERICK
HAROLD FITZMAURICE.
